(No Model.)

J. DUBELMAN.

MACHINE FOR MAKING COILED SPRINGS.

No. 261,319.

Patented July 18, 1882.

UNITED STATES PATENT OFFICE.

JOHN DUBELMAN, OF DETROIT, MICHIGAN, ASSIGNOR OF ONE-HALF TO
GEO. WM. KUEHN, OF SAME PLACE.

MACHINE FOR MAKING COILED SPRINGS.

SPECIFICATION forming part of Letters Patent No. 261,319, dated July 18, 1882.
Application filed April 17, 1882. (No model.)

To all whom it may concern:

Be it known that I, JOHN DUBELMAN, of Detroit, in the county of Wayne and State of Michigan, have invented new and useful Improvements in Machines for Making Coil-Springs; and I do hereby declare that the following is a full, clear, and exact description thereof, reference being had to the accompanying drawings, which form a part of this specification.

The nature of this invention relates to certain new and useful improvements in the construction of machines for the manufacture of that class of springs known as "coil" or "spiral" springs; and the invention consists in the peculiar construction of the parts of the machine and their various combinations, by means of which such springs can readily be made with certainty and rapidity and of any required closeness or looseness in the coils, as more fully hereinafter described.

Figure 1 is a perspective view of the improved machine. Fig. 2 is an end elevation of the coiling-wheel and spindle with various parts removed, and Fig. 3 is a vertical central section of the spreader-bar.

In the accompanying drawings, A represents the standards of the machine, which carry the operating parts, said standards rising from the bed B, which is provided with the prolongation C. The main driving-shaft D runs in suitable boxes, E, secured to the standards, and is driven from any suitable source of power. Upon this shaft is secured the gear-pinion F, which engages with the spur-wheel G, which is secured to the shaft H, journaled in boxes I, secured between the standards A. Upon this shaft H is secured the pinion J, which engages with the pinion K upon the shaft L, journaled in boxes M N, which have a vertical movement between the standards A upon the vertical guides O. The box M is raised or lowered, as occasion may require, by means of the screw P, while the opposite end of the shaft and its box N are raised or lowered by the operation of the machine, as hereinafter explained. Upon the outer overhanging end of the shaft L is the heavy steel-faced wheel Q. The shaft H is threaded, as shown, and terminates in a socket, S, to receive the end of the spindle R, which is secured in said socket

by the set-screws a. This spindle is made removable, so that spindles of different sizes may be employed in manufacturing springs of larger or smaller diameters.

T is an arm or bracket secured to the standard A, and upon its free end is journaled a groove-wheel, U.

V is a box sleeved upon the shaft L and laterally adjustable thereon, and is secured thereon from lateral displacement by the set-screw b, which engages in an annular groove (not shown) in the shaft L, without interfering with the free rotation of the latter, or collars secured on each side of the box V may be used for the same purpose. This box carries a hanger, W, constructed to embrace the shaft H, but without contact therewith, and terminates in a slotted guide, X, through which the arm Y has a reciprocating motion. The inner end of this arm Y terminates in a tongue, A', which is designed to engage at certain times with the thread upon the shaft H, and by means of this engagement the arm with its attachments is drawn toward the rear of the machine until the tongue is allowed to drop again. The opposite end of this arm Y is pivotally secured to the rod B', which has a reciprocating motion in the boxes C', secured upon the top of the supports D', and upon this arm is a coil-spring, E', adapted to retract the rod and the arm Y when the tongue A' has dropped out of engagement with the threaded portion of the shaft H. To the opposite end of this arm B' are secured the spring-jaws E'', made substantially in the form shown, and these are projected and retracted with the reciprocation of the rod B'.

F' is a bracket, carrying a spreader-bar, G', so pivoted that on the projection of the rod B' it will spread or divide the spreaders E'' as the contracted parts thereof pass the suspended spreader until such projection brings the enlarged space H' forward to the point occupied by the spreader, when the springs will assume their normal position; and in the retraction of the bar B' the spreader will be raised up until in the retraction of the jaws E'' it will drop into the position shown in the drawings.

To the end of the rod B' is hinged the stop I, which, in the projection of the rod B', depresses the lever J', fulcrumed at c, and raises

the opposite end of said lever, which is provided with a lip, *d*, for the purposes hereinafter described. This stop, on the retraction of the rod *B'*, will swing upward, its point resting 5 lightly on the top of the lever *J'* until it falls off the end thereof, when it will assume the position shown in the drawings, and the spring *e*, under the lever *J'*, will elevate that end of it.

It is important in the construction of this 10 machine that the position of the shaft *H* and its spindle *R* shall not be in the vertical plane of the axis of the shaft *L*, but to one side thereof, as shown in Fig. 2, and the adjustability of the parts is such as to allow springs of 15 larger or smaller diameter or of larger or smaller wire to be made by simply changing the spindle *R* and vertically adjusting the box *M* to correspond.

In the operation of the machine, the box *M* 20 will adjust itself by the interposition of the wire in the process of manufacturing springs. The size of the wire and the diameter of the spring being determined upon, a spindle corresponding to the internal diameter of the 25 spring is secured in the end of the shaft *H* and the box *M* adjusted to the required thickness of the wire, the cogs on the pinions being sufficiently long to allow of such adjustment. The end of the wire is fed over the spool *U* 30 and over the spindle *R*, and as it passes under the wheel *Q* it raises the box *N* to a level with the box *M*, and the weight of the wheel bends the wire to conform to the shape of the spindle. As the coils are formed upon such spindle the projection of the rod *B'* is caused by 35 the tongue *A'* engaging with the thread upon the shaft *H*. This projection causes the stop *I* to depress the end of the lever *J'* and force its tongue between the coils of the wire to 40 spread them, and the greater or lesser spread between the coils will be obtained by using a broader or narrower tongue, *d*, which may be done at will either by conforming such tongue to slip onto the end of the lever *J* or having 45 a number of such levers with different-sized tongues, one of which may be inserted in the machine when required for use. By using levers of different length the length of open coil can be easily altered. This projection 50 also of the rod *B'* causes the spring-jaws to likewise project and be spread apart by the spreader *G* until such jaws will embrace the two opposite sides of the spindle *R* with the spring upon it. As soon as the piece of wire fed 55 upon the spindle *R* is completely coiled it will, by reason of its engagement with the tongue *d* of the lever *J*, be drawn out from under the wheel *Q*, and the latter, dropping down by its weight, will now lower and disengage the tongue 60 *A'* of the lever *Y* from the convolutions of the thread on shaft *H*. The disengagement allows the spring *E'* to retract the shaft *B'*, the jaws *E²* *E²* thereby pulling the finished coil from the templet *R*. During this retrograde movement the spreader-bar *G*, being free to swing

forward, is raised out of the way without spreading the jaws. The coil withdrawn from the templet *R* is held loosely enough by the jaws *E²* *E²* to fall out and down into the tempering-bath. If not, the re-opening of the jaws 70 at the beginning of a new operation will allow them to do so.

The guide *X* and yoke *W* are kept in proper vertical position by a pin, *l*, moving in a longitudinal slot, *m*, in the bed *B*.

What I claim as my invention is—

1. The combination, with the rotating spindle *R*, of the heavy wheel *Q*, secured to a shaft mounted in two bearings, one of which is adjusted by a set-screw and the other adapted to have a free vertical movement, substantially as described.

2. The combination, with the standard *A*, of the bearing *M*, the screw *P*, for adjusting said bearing, the bearing *N*, adapted to have a free vertical movement in the standard, the shaft *L*, journaled in the bearings *M* *N*, the heavy wheel *Q*, mounted on the shaft *L*, the spindle *R*, and means for rotating the shaft *L* and spindle *R* in opposite directions, substantially as 90 described.

3. The combination, with the heavy wheel *Q* and the spindle *R*, rotating in opposite directions, of the spring-jaws *E²* *E²* and connections, substantially as described, between said 95 springs and the shaft of the spindle *R*, whereby a formed spring may be removed automatically from the spindle, as set forth.

4. The combination, with the spindle *R* and wheel *Q*, of the threaded shaft *H*, the arm *Y*, the rod *B'*, spring *E'*, springs *E²*, having narrowed center portions, the standard *F*, and the spreader *G*, so pivoted in said standard that it can move past a vertical line only in one direction, substantially as described.

5. In a machine for winding coil or spiral springs, the arm *Y*, rod *B'*, spring *E'*, springs *E²*, and spreader *G'*, in combination with the threaded shaft *H*, for the purpose of withdrawing the coiled wire from the spindle of the machine, substantially as set forth.

6. In a machine for winding coil or spiral springs, and in combination with the rod *B'* and spring-jaws *E²*, devices for opening and closing said jaws automatically, the hinged 115 stop *I'* and lever *J'*, substantially as and for the purposes set forth.

7. In a machine for the manufacture of coil or spiral springs, and as a means for supporting the end of the arm *Y*, the support *W*, pendent from and supported by the box *V*, adjustably secured upon the shaft *L*, substantially as set forth.

8. The combination, with the spindle *R* and the wheel *Q*, the shaft *L* and the threaded 125 shaft *H*, of the hanger *W*, having guide *X*, the arm *Y*, the springs *E²*, and connecting mechanism, substantially as described, between the arm *Y* and the springs *E²*, as set forth.

9. The combination, with the spindle *R*,

wheel Q, and the threaded shaft H, of the arm Y, bar B', springs E', spring-jaws E², spreader-bar G, hinged stop I, and the lever J, substantially as described.

5 10. The combination, with the spindle R and the wheel Q, of the threaded shaft H, the arm Y, the bar B', the hinged stop I, and the le-

ver J', having lip d and spring e, substantially as described.
